UNITED STATES PATENT OFFICE.

LEWIS T. RHOADES, OF MONT CLARE, PENNSYLVANIA, ASSIGNOR TO NEW YORK COIL COMPANY, INCORPORATED, OF NEW YORK, N. Y.

IGNITION DEVICE FOR INTERNAL-COMBUSTION ENGINES.

1,155,372.

Specification of Letters Patent.

Patented Oct. 5, 1915.

Application filed March 6, 1915. Serial No. 12,530.

To all whom it may concern:

Be it known that I, LEWIS T. RHOADES, a citizen of the United States, residing at Mont Clare, in the county of Montgomery and State of Pennsylvania, have invented 5 certain new and useful Improvements in Ignition Devices for Internal-Combustion Engines, of which the following is a specification.

10 My invention relates to improvements in ignition devices for internal combustion engines, the object of the invention being to provide a mechanism of the character stated which will insure a uniform spark at every 15 explosion regardless of the speed of the engine.

To those skilled in the art, it is well known that when an induction coil of the non-vibrating type is employed in connection with a circuit maker and breaker of the conventional type, that the cam surfaces which are caused to bring contact points together for the purpose of closing the circuit through said induction coil, and then opening 25 the circuit to produce a spark from such coil, that it is necessary to have the cam of such length that the circuit will be held closed sufficiently long to allow saturation of the coil in order that the proper spark 30 may be produced. It is of course evident that the cam must be sufficiently long or have enough dwell to allow saturation at the highest speed, therefore at all lower speeds, the contact points are together much longer 35 than is necessary, resulting in a great waste of current, and due to the excessive amount of current passing when the current is broken, the large arc or spark produced at the contact points, results in the rapid deterioration of such contacts.

40 With my improved construction, I employ a cam on the circuit breaker arm of a peculiar shape, so that I cause more and more contact or dwell upon the cam as the speed increases, so that the amount of current drawn will be practically uniform throughout the entire range of speed of the engine or engines upon which the device is attached.

45 A further object of my invention is to provide centrifugal means for advancing and retarding the spark, whereas in the majority of ignition systems now used, this advance and retard is manually operated by 50 various means of construction. I make use

of the advancing and retarding of the spark mechanism to actuate the cam in a direction at right angles to its rotation for the purpose of maintaining a constant current supply.

55 With these and other objects in view, the invention consists in certain novel features of construction and combinations and arrangements of parts as will be more fully hereinafter described and pointed out in the 60 claims.

65 In the accompanying drawings: Figure 1 is a plan view illustrating my improvements. Fig. 2 is a view in longitudinal section partly in elevation. Fig. 3 is a view in 70 transverse section on the line 3-3 of Fig. 2. Fig. 4 is a fragmentary view partly in elevation and partly in section illustrating the pin which compels the longitudinal movement of the rotary cam, and Fig. 5 is a frag- 75. mentary view partly in section and partly in elevation illustrating the face of the circuit breaker arm showing the shape of the cam thereon.

80 While, of course, my improved device may be located at any position so that one part may be vertical and another horizontal, for convenience of description, I shall hereinafter assume the parts to be in the position indicated on the drawings.

85 1 represents a casing in which a supporting plate 2 is located having a central opening 3, in which a collar 4 on a sleeve 5 is mounted to turn. The sleeve 5 is supported upon a reduced portion 6 of time shaft 7.

90 A cross bar 8 is secured to the time shaft at the juncture of its larger and smaller diameters, and on this cross bar 8, a pin 9 is secured and engages in a recess 10 in a head 11 on the lower end of sleeve 5. The walls 95 of this recess 10 are curved or at an angle, so that they operate as cam surfaces and when the head 11 and sleeve 5 are turned independently of the time shaft, the sleeve 5 will be caused to move longitudinally by 100 reason of the cam action of the pin 9 against the wall of the recess 10.

105 A rotary cam member 12 is secured to the sleeve 5 above the collar 4, and is provided on its periphery with a series of cams 13 adapted to contact with the cam 14 on the face of a circuit breaker arm 15, and a rotary wiper 16 is provided on plate 2 which maintains the cams 13 clean and free from 110 particles of any sort.

The circuit breaker arm 15 is secured to a block 17 having rotary mounting in a bracket 18 on plate 2, and a coiled spring 19 connects the bracket with the arm to normally hold the arm against a stop 20^a on plate 2, and maintain the contact 21 carried by spring tongue 20 on arm 15 away from stationary contact 22, which latter may form the part of a binding post 23 as clearly shown.

The bar 8 above referred to supports a centrifugal governor which comprises two relatively heavy arms 24 which are pivotally supported on pins 25 secured to the respective ends of bar 8. These arms 24 are provided at their pivoted ends with relatively flat fingers 26, having recesses 27 therein to receive pins 28 on the head 11 of sleeve 5, and cause the head to turn when the arms are thrown outward by the centrifugal force.

Extensions 29 are provided on the fingers 26 which are in position to engage the sleeve 5 and limit the pivotal movement of the governor arms, and coiled springs 30 connect the arms 24 and resist the outward throw of the arms as will be readily understood.

The cam 14 on arm 15 is widest at its upper end, and tapers to a point near its lower end as shown at 31, and then the two edges of the cams extend to the lower edge of the arm and are parallel so that this lower narrowest portion of the cam is of the same length or width for a considerable distance from the lower edge of the arm upwardly. It will also be noted that the edge of the cam 14 nearest the pivoted end of the arm is straight throughout. This is the edge of the cam which first receives the contact of the cams 13 on the rotary cam member 12, and the length of contact is determined by the position of the cam member 12 on the time shaft, and this position is controlled by the governor arms 24 in accordance with the speed of the engine.

To hold the rotary cam member in its lowered position, and return it to such position, I provide a coiled spring 32 located around the reduced end 6 of time shaft 7, and between a fixed collar 33 and the rotary cam member, exerting a constant pressure on the latter, and normally holding the same at its position for lowest speed.

In starting, and until a relatively high speed is attained, the cams 13 engage the narrowest portion of cam 14 on arm 15, but as the speed of the engine increases, the movement of the arms 24 will cause the head 11 to turn, and due to the cam action of pin 9 in recess 10, sleeve 5 with the cam member 12 thereon will be moved longitudinally of the time shaft, so that a greater length of cam surface 14 is presented to the cams 13, and the length of this contact or dwell is just sufficient at all speeds to permit the proper

saturation of the induction coil, so that when the circuit is broken, the proper spark will be made regardless of the speed of the engine, and without wasting any current while running at low speeds, hence regulating the spark automatically by the movement of the rotary cam member longitudinally of the time shaft, and at right angles to the direction of turning movement.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a movable circuit breaker arm, of a cam positioned transversely of the arm and tapering from one end toward the other, a rotary member having cams thereon adapted to engage the cam of the circuit breaker arm, and means for moving one of said members relative to the other, substantially as described.

2. The combination with a movable circuit breaker arm, of a cam positioned transversely of the arm and tapering from one end toward the other, a rotary member having cams thereon adapted to engage the cam of the circuit breaker arm, and means for moving the rotary member transversely of the circuit breaker arm, substantially as described.

3. The combination with a movable circuit breaker arm, of a cam positioned transversely of the arm and tapering from one end toward the other, a rotary member having cams thereon adapted to engage the cam of the circuit breaker arm, and a centrifugal governor constructed to move the rotary member at right angles to the circuit breaker arm, substantially as described.

4. The combination with a circuit breaker arm having a tapering cam thereon, said cam extending transversely of the circuit breaker arm and tapering from one end toward the other, of a rotary cam engaging the cam on the arm, a time shaft on which said rotary cam is mounted, and a governor on the time shaft constructed to move the rotary cam longitudinally, substantially as described.

5. The combination with a circuit breaker arm having a tapering cam thereon, said cam extending transversely of the circuit breaker arm and tapering from one end toward the other, of a time shaft, a sleeve on the time shaft, a rotary cam secured to the sleeve and engaging the cam on the circuit breaker arm, and a governor mounted on the time shaft and constructed to move the

sleeve longitudinally, substantially as described.

6. The combination with a circuit breaker arm having a tapering cam thereon, of a time shaft, a sleeve on the time shaft, a rotary cam secured to the sleeve and engaging the cam on the circuit breaker arm, a head on the sleeve having a recess therein, a pin projecting in the recess and having cam engagement with the walls of the recess, and a governor constructed to turn the head and cause the longitudinal movement of the sleeve in accordance with the speed of the shaft, substantially as described.

15 7. The combination with a circuit breaker arm having a tapering cam thereon, of a time shaft, a sleeve on the time shaft, a rotary cam secured to the sleeve and engaging the cam on the circuit breaker arm, a head on the sleeve having a recess therein, a pin projecting in the recess and having cam engagement with the walls of the recess, governor arms pivotally supported at one end and engaging the head, whereby 20 the outward movement of the arms compels the longitudinal movement of the sleeve, substantially as described.

25 8. The combination with a circuit breaker arm having a tapering cam thereon, of a time shaft, a sleeve on the time shaft, a rotary cam secured to the sleeve and engaging the cam on the circuit breaker arm, a head on the sleeve having a recess therein, a pin projecting in the recess and having cam engagement with the walls of the recess, governor arms pivotally supported at one end and engaging the head, whereby the outward movement of the arms compels the longitudinal movement of the sleeve, springs 30 connecting the arms, and fingers on the arms engaging the sleeve limiting the outward movement of the arms, substantially as described.

35 9. The combination with a circuit breaker arm having a tapering cam thereon, said cam extending transversely of the circuit breaker arm and tapering from one end toward the other, of a rotary cam engaging the cam on the arm, a governor constructed to move the rotary cam at right angles to its rotation, and a spring exerting pressure on the rotary cam member normally holding the latter in position to engage the narrowest face of the cam on the circuit breaker arm, substantially as described.

40 10. The combination with a circuit breaker arm having a tapering cam thereon, said cam extending transversely of the circuit breaker arm and tapering from one end toward the other, of a rotary cam engaging the cam on the arm, a centrifugal governor constructed to move the rotary cam at right angles to its rotation, and a spring exerting pressure on the rotary cam member normally holding the latter in position to en-

gage the narrowest face of the cam on the circuit breaker arm, substantially as described.

45 11. The combination with a circuit breaker arm having a tapering cam thereon, 70 said cam extending transversely of the circuit breaker arm and tapering from one end toward the other, of a rotary cam engaging the cam on the arm, a time shaft on which said rotary cam is mounted, a governor on 75 the time shaft constructed to move the rotary cam longitudinally, and a spring exerting pressure on the rotary cam member normally holding the latter in position to engage the narrowest face of the cam on 80 the circuit breaker arm, substantially as described.

50 12. The combination with a circuit breaker arm having a tapering cam thereon, 85 said cam extending transversely of the circuit breaker arm and tapering from one end toward the other, of a time shaft, a sleeve on the time shaft, a rotary cam secured to the sleeve and engaging the cam on the circuit breaker arm, a governor 90 mounted on the time shaft and constructed to move the sleeve longitudinally, and a spring exerting pressure on the rotary cam member normally holding the latter in position to engage the narrowest face of the 95 cam on the circuit breaker arm, substantially as described.

55 13. The combination with a circuit breaker arm having a tapering cam thereon, 100 of a time shaft, a sleeve on the time shaft, a rotary cam secured to the sleeve and engaging the cam on the circuit breaker arm, a head on the sleeve having a recess therein, a pin projecting in the recess and having cam engagement with the walls of the recess, a governor constructed to turn the head and cause the longitudinal movement of the sleeve in accordance with the speed of the shaft, a spring exerting pressure on the rotary cam member normally holding the latter in position to engage the narrowest face of the cam on the circuit breaker arm, substantially as described.

60 14. The combination with a circuit breaker arm having a tapering cam thereon, 115 of a time shaft, a sleeve on the time shaft, a rotary cam secured to the sleeve and engaging the cam on the circuit breaker arm, a head on the sleeve having a recess therein, a pin projecting in the recess and having cam engagement with the walls of the recess, governor arms pivotally supported at one end and engaging the head, whereby the outward movement of the arms compels the longitudinal movement of the sleeve, and a spring exerting pressure on the rotary cam member normally holding the latter in position to engage the narrowest face of the cam on the circuit breaker 125 arm, substantially as described.

15. The combination with a circuit breaker arm having a tapering cam thereon, of a time shaft, a sleeve on the time shaft, a rotary cam secured to the sleeve
5 and engaging the cam on the circuit breaker arm, a head on the sleeve having a recess therein, a pin projecting in the recess and having cam engagement with the walls of the recess, governor arms pivotally sup-
10 ported at one end and engaging the head, whereby the outward movement of the arms compels the longitudinal movement of the sleeve, springs connecting the arms, fingers on the arms engaging the sleeve limiting
15 the outward movement of the arms, and a spring exerting pressure on the rotary cam member normally holding the latter in position to engage the narrowest face of the cam on the circuit breaker arm, substan-
20 tially as described.

16. A device of the character described, comprising a stationary contact, a movable circuit breaker arm normally spaced from the stationary contact, a rotary member having cams thereon, a cam on the circuit breaker arm varying in length and positioned transversely of the circuit breaker arm, said last-mentioned cam engaged by the cams on the rotary member, and centrifugal means compelling the rotary member 25 to move at right angles to the circuit breaker arm, substantially as described.
30

In testimony whereof I have signed my name to this specification in the presence of two subscribing witnesses.
